ROTARY ENGINE.

1,286,900.

Specification of Letters Patent. Patented Dec. 10, 1918.

Application filed March 18, 1918. Serial No. 223,105.

To all whom it may concern:

Be it known that I, ALBERT C. ASHCRAFT, a citizen of the United States, residing at Colfax, in the county of Whitman and State 5 of Washington, have invented new and useful Improvements in Rotary Engines, of which the following is a specification.

This invention relates to improvements in rotary engines, and while the specific form 10 shown is designed as an explosion engine, my invention is not limited to this type of engine as it will be understood that a mere engineering change of the inlet and exhaust ports, would render the structure equally 15 advantageous as a steam engine.

In accordance with my invention, an engine casing is provided having a rotor chamber, which is circular, and provided with one or more compression chambers in intersecting and communicating relation with the rotor chamber. One or more intake 20 chambers, in intersecting relation with the rotor chambers, are provided, the number of intake chambers equaling the number of 25 compression chambers. In the most improved construction, the compression and intake chambers are semi-cylindrical but are greater than a semi-circle and the line of intersection is radially inwardly from the 30 axis, or greatest diameter of such chamber.

My invention includes an improved form 35 of rotor which is concentrically mounted in the casing to rotate in said rotor chamber with a uniform annular space between the periphery of the rotor and the perimeter of the rotor chamber. My improved rotor has one or more pistons which project radially 40 in the motor chamber sufficiently to engage their outer edges with the perimeter of the rotor chamber, the sides of the pistons and the sides of the rotor being also in engagement.

A novel feature of my invention consists 45 in improved packing for the peripheral edges of the pistons and the sides thereof, extending radially inwardly beyond the gas chamber formed by the rotor in the rotor chamber. In accordance with my improved packing, the pressure seeking escape beyond 50 the packing serves to energize the latter to prevent such escape.

In each compression chamber my invention includes novel rotary valve means which

co-act with the compression chamber and the periphery of the rotor to act as an abutment arresting escape of the gases being compressed by an advancing piston, or likewise arresting escape of an ignited charge, so that on one side of each valve, an ignited charge will be imparting rotary thrust to 55 one piston while on the other side of said valve, an advancing piston will be compressing a charge. My novel valve means is constructed, in combination with the novel form of pistons, so that as a piston approaches the valve, the latter will ride up on the piston and pass into the compression chamber to pocket the charge therein so as not only to retain the charge, but permit the 60 piston to pass the valve. During the interval or distance which the piston travels across the compression chamber, my invention provides for gas-tight engagement of the piston edge with the compression valve, to preserve the independence of the gas 65 chambers formed between adjacent pistons. After the charge compressing piston has passed the valve, and its compression chamber, and again engages the perimeter of the 70 rotor chamber, the compression valve rides down along the piston and into engagement with the periphery of the rotor to open the compression chamber and permit of the ignited charge acting upon that piston which just previously had compressed this same 75 charge. Thus each compression valve acts as a back abutment for an exploded charge and as a front abutment for the charge being compressed.

My invention also includes a novel form 80 of intake valve which is preferably oscillatory, and which when in an open position, permits of an advancing piston inducing an inflow charge behind it while an exhausting piston is scavenging the burnt gases. In 85 other words, my improved intake valve, acts as an abutment in the rear of an advancing piston inducing an inflow of a charge, and in front of a following piston effecting the discharge of burnt gases.

In addition to the novel form of packing for the pistons, my improved compression and intake valves are also equipped with a like form of packing, both forms of packing being preferably metallic.

My invention has many other objects and

features which will be more particularly described in connection with the accompanying drawings and which will be more specifically pointed out in and by the appended 5 claims.

In the drawings:—

Figure 1, is a view in side elevation of the preferred form of my rotary engine designed for use as an explosion engine.

10 Fig. 2, is a view partly in elevation, and partly in section, taken on line 2—2 of Fig. 1, and showing the intake abutment valves in an open position and the compression valves in an abutment position behind exploded charges and in front of charges being compressed.

15 Fig. 3, is a view similar to Fig. 2, with the intake valves closed and the compression valves in a position to pocket the compressed charges in the compression chambers.

20 Fig. 4, is sectional elevation view on line 4—4 of Fig. 1, showing the disposition of the actuating cam for the compression valve when the latter is in the position shown in 25 Fig. 2.

Fig. 5, is a view similar to Fig. 4, showing the cam actuating means in the position which it would assume with the compression valves as shown in Fig. 3.

30 Fig. 6, is a view similar to Fig. 5, showing the cam actuating means as it is about to go over dead center and rotate the compression valves into a position to open the compression chamber and release the compressed 35 charge for ignition.

Fig. 7, is a sectional view on line 7—7, of Fig. 1, showing the cam actuating means for the abutment intake valves in the position which it would assume when the valves 40 are disposed as shown in Fig. 2.

Fig. 8, is a view similar to Fig. 7, showing the actuating means in the position which it would assume to close the intake abutment valves, as shown in Fig. 3.

45 Fig. 9, is a view similar to Fig. 8, showing the actuating mechanism in the position which it would assume when the abutment intake valves close down along the receding piston.

50 Fig. 10, is a longitudinal sectional view on line 10—10 of Fig. 2, of one of the intake abutment valves detached from the engine.

Fig. 11, is a view in elevation of Fig. 10, looking in the direction of the arrow.

55 Fig. 12, is a sectional view on line 12—12 of Fig. 10.

Fig. 13, is a sectional view on line 13—13 of Fig. 2, showing the peripheral construction of the rotor.

60 Like characters of reference designate similar parts throughout the different figures of the drawings.

As shown, and referring to the specific embodiment of my invention wherein it is 65 designed to operate as an explosion engine,

the invention includes a generally cylindrical casing 1, having heads 2 and 3. The casing forms a cylindrical rotor chamber 4, and the side walls of said chamber are indicated at 5, and the peripheral wall at 6.

70 A rotor shaft 7 is journaled in suitable bearings in the casing in concentric relation with respect to the peripheral wall 6, and at this point attention is directed to the fact that the peripheral wall 6 is a cylindrical wall. Keyed or otherwise secured to the rotor shaft 7, is a rotor having a hub 8. Spokes 9 radiate from said hub and said spokes are shown inclined or canted transversely to their longitudinal axes, and at an 75 angle with respect to their direction of rotation, so that rotation of the spokes will act as a fan to generate currents of air as a cooling medium. Formed integral with the spokes 9, is a peripheral rim 10, suitably 80 ribbed, as indicated at 11, and having lateral flanges 12. The lateral flanges 12 are in tight working engagement against the heads 2 and 3 and the rim 10 is in concentric relation with respect to the periphery 6, of the casing 1. Thus there will be formed between the periphery of the rotor and the peripheral wall 6, a rotor chamber.

85 Projecting from the rotor toward and into contact with the peripheral wall 6, is a plurality of pistons, all of which are identical in construction and function, but which will for convenience be separately designated by different numerals 13, 14, 15 and 16, to facilitate an understanding of the 90 description of operation, which will later appear. The peripheral edges of the pistons are in gas-tight wiping engagement with the wall 6, and the lateral sides are in gas-tight engagement with the heads 2 and 3. 95 A novel form of packing employed will be 100 later described.

105 As will now appear from Fig. 2, the pistons separate the rotor chamber into a plurality of gas compartments, some of which 110 will hold the compressed charge, while others will hold the ignited charge, and still others will be exhausting the burnt charges.

115 As I have shown four pistons, I provide two compression chambers and two intake chambers. The compression chambers, which are identical in construction, are for convenience designated by separate numerals 17 and 18, and said chambers are formed integral with the casing and are greater 120 than a semi-circle and are intersected by the rotor chamber.

125 The compression chambers 17 and 18, are shown diametrically disposed at opposite points of the casing and it will be seen that they communicate with the rotor chamber by relatively large areas 19 and 20, and it will also be seen that the diametrical dimensions of these intersecting areas of the compression chambers with the rotor chamber, 130

are somewhat less than the maximum diameter of either compression chamber.

Interposed between the compression chambers, and at diametrically opposite points 5 of the casing are provided intake chambers 21 and 22, both being identical in formation. The intake chambers and the compression chambers are disposed equidistantly about the circumference of the engine casing and 10 the intake chambers are intersected by the rotor chamber at points below their greatest diameter, as indicated at 23 and 24. Each intake chamber has an inlet opening to such chamber, the inlet of chamber 21 15 being designated at 25, and the inlet of chamber 22 being designated 26. The casing 1 is ported at 27 and 28, and suitable flanged terminals 29 and 30 serve for connections with pipes leading from the source 20 of supply of a carbureted mixture. In advance of each intake chamber, with respect to the rotation of the rotor, and closely adjacent to each intake chamber, are exhaust ports 30 and 31, which open outwardly from 25 the rotor chamber and connect by ports 32 and 33 through flanged terminals 34 and 35, for discharge of the exhaust or burnt gases.

I will next refer to the intake valves, both of which are identical in structure and 30 operation, but each of which is generally indicated by different reference numerals 36 and 37. A description of one valve will be sufficient, and reference will be made to Figs. 2, 10, 11 and 12.

35 In cross section, the intake valve is semi-cylindrical, as indicated at 38, and is provided with an arcuate piston edge abutment wall 39. The arc of this wall has a center coincident with the axis of shaft 7, so that 40 when the intake valve is in the position shown in Fig. 3, the edge of the piston 16 or 14 will be in gas-tight wiping engagement with the arcuate abutment wall 39, until the piston is again in engagement with 45 the periphery 6, of the casing 1. The intake valve 38 is suitably hubbed at 40, to receive an actuating shaft 41, which will be mounted in suitable bearings formed in the heads 2 and 3. Description of the means 50 for actuating the valves will be later taken up. The diameter of the intake valve is such that when the same is in the position shown in Fig. 2, a portion of its periphery will be in engagement with the periphery 55 of the rotor, between the pistons, so that when the valve is in this position, it will act as an abutment in the rear of an induced charge, and it will act as an abutment in front of the burnt gases being exhausted.

60 The compression abutment valves are generally designated at 42 and 43, and both are identical in structure and operation, so that only one need be described in detail. Valve 42 is substantially I-shaped in cross 65 section and is mounted upon a compression

valve shaft 44. A like shaft 45 is provided for valve 43. Both shafts will have suitable bearings in the heads 2 and 3, and the actuating means therefor will be later described. It will be noticed that shaft 44 is centrally 70 disposed as regards the extreme edges 46 and 47, so that pressure on either side of said abutment compression valve will be equally distributed over equal areas, therefore making the valve balance, as regards 75 opposing pressures on each side and also on opposite sides thereof.

It will also be noted that the shaft portion of the valve is enlarged, as indicated at 80 48 and 49, convexly, and that these convex hubs or central portions merge into oppositely extending concavely curved portions 50, 51, 52 and 53. These concave portions are struck from a center coincident with the axis of shaft 7. Therefore, when 85 the abutment compression valves are in the position shown in Fig. 2, where they pocket the compressed charge in the outer portions of the compression chambers, these curved faces will be engaged by the edges of the 90 pistons as the latter pass across the face at the line of intersection of the compression chambers with the rotor chamber.

Reference will next be made to a novel construction whereby the intake abutment 95 valves, and also the compression abutment valves may ride up on certain faces of the pistons, and downwardly on other faces, in a manner to preserve the peripheral engagement of the valves with the rotor and pistons and prevent escape of the gases from one intervening chamber between two pistons into another intervening chamber between the next two pistons.

First referring to piston 13, the same is 105 provided with a curved compression or exhaust face 54, in front of which the gases are propelled into compression or scavenged or expressed from the rotor chamber, as the case may be. The curve of face 54 is generated so that the edge 47 can ride up onto the piston, as the latter advances toward valve 42, the valve being accelerated in its rotative movement in order to provide for the edge 47 passing into the compression 110 chamber 17 just as the piston 13 reaches the end 55, of wall 6. Thus one portion of the valve will be rotating toward the advancing piston in the function of pocketing the gas compressed by said piston into the 115 compression chamber, as will be detailed more fully hereinafter. When the valve is in the position shown in Fig. 3, the edge of the piston 13 will be in wiping engagement with the curved face 53, and the valve will 120 be held in the position shown in Fig. 3, until the piston 13 reaches the hub portion or enlargement 49. After the piston 13 has passed to the right of enlargement 49, then the valve will be suddenly shifted to bring 125 130

the curved face 52 into engagement with the edge of the piston 13, and such engagement will be maintained until the piston 13 reaches portion 56, of wall 6. Thereupon, 5 the edge 46 will travel downwardly or radially inwardly along the rearwardly curved face 57, of piston 13. This movement of the valve releases the compressed charge for ignition against what I shall call 10 the explosion face 57 of the piston 13. The edge 46 will continue to move downwardly until it reaches the periphery or rim of the rotor, whereupon the compression valve will have made one complete revolution from the 15 position shown in Fig. 2, to the position just described.

Attention will next be directed to the co-action between the intake valve and the rotor.

20 In the position shown in Fig. 2, the intake valve 36, is adjusted so that a portion of its periphery is in peripheral engagement with the rotor and the arcuate abutment face is located inside the intake chamber 25 so as to open the intake 25 for passage of an induced charge into the rotor chamber. In this position, the intake valve forms the rear abutment to confine the induced charge between said valve 36 and piston 13. Rearwardly of valve 36, with respect to the direction of rotation, the advancing piston 16 is exhausting the burnt gases through discharge outlet 30, and therefore the abutment valve 36, forms a front abutment to 30 prevent escape of the burnt gases past valve 36. As piston 16 approaches valve 36, the latter will be turned at accelerated speed with the peripheral portion of the valve 36 riding up on the curved face of piston 16 35 until the parts reach the position shown in Fig. 3. Here the arcuate abutment of the intake valve will be presented to the piston 16, for the latter to pass across the valve, and into engagement with the next following 40 section of the wall 6. In this position of the intake valve, as shown in Fig. 3, the intake is closed. Now it will be seen that valve 36 has been turned in a clock-wise direction from the position shown in Fig. 2, to 45 the position shown in Fig. 3, to close the intake and permit the piston 16 to pass the valve. After the piston 16 has passed the valve, then the latter will be actuated in a contra-clockwise direction to open the intake 50 55 25, and it will assume the position shown in Fig. 2, behind the piston 16. Thus the compression valves are rotary valves, whereas the intake valves are oscillatory valves.

While the operation of the compression 60 and intake valves, in combination with the rotor and its pistons, may be clear from the foregoing, this operation may be briefly recapitulated as follows:—

Referring to Fig. 2, it will be seen that the 65 pistons 13 and 15 are drawing induced

charges through the inlets 25 and 26, respectively, the intake valves 36 and 37 being open. The abutment compression valves 42 and 43 are shown in peripheral engagement with their respective compression chambers 70 and also with the rotor, and the forward or compression faces of pistons 13 and 15 will be compressing a charge into the compression chambers 17 and 18, in advance thereof. Here, attention is directed to the fact that 75 the pressure of the compressed charge on the left hand face of abutment compression valve 42, will be equally distributed on both sides of shaft 44 so that this valve will be balanced under the pressure exerted against 80 it. This feature greatly relieves the actuating means, of whatever nature I may employ. It also simplifies the mechanism and permits of a highly responsive action of the compression valves as a result of operation 85 of their actuating means. Still referring to Fig. 2, it will be seen that pistons 14 and 16, as regards their forward curved faces, are ejecting the burnt gases through exhaust outlets 31 and 30, the intake valves being in 90 peripheral engagement with the rotor to act as abutments whereby the burnt gases are necessarily forced out through outlets 30 and 31. The rear faces of pistons 14 and 16 are under the propulsive thrust of ignited 95 charges on the right hand face of compression valve 42 and on the left hand face of compression valve 43. Here again, attention is directed to the fact that the compression valve 42, forming an abutment behind the exploded charge acting on piston 14, receives just as much pressure above shaft 44 as below this shaft, and therefore the valve will be in an equilibrium of balance which will not in any way tend to force the valve 105 out of position.

My invention is not concerned with any special means of ignition, and no means are shown, as I am aware that ignition is a matter of separate invention. However, attention is directed to the fact that as the pistons 110 13 and 15 pass to the right and to the left, respectively, of compression valves 42 and 43, as they are in the act of doing in Fig. 3, the compression valve edges 46 will ride down on the rearwardly curved faces of these pistons, and the valves will be accelerated in such movement, therefore there will be a quick opening for the exploded charge whereby the latter will instantly be 115 free to positively direct the full force of its propulsive thrust against these pistons as the latter recede from their respective compression valves. This quick opening of the compression chambers for instant discharge 120 at full capacity of the ignited charge, completely avoids any back pressure or waste of energy and localizes the full force of the ignited and exploded charge upon the piston. After the compression valves have reached 125 130

a position where they are in peripheral engagement with the rotor, between two adjacent pistons, as shown in Fig. 2, then the compression valves are held stationary until 5 the next following piston advances, as in the case of piston 13 in Fig. 2, whereupon the compression valves will be accelerated in their movement toward their advancing pistons to close into their respective compression 10 chambers and permit the pistons to pass, as has been previously described.

I will next describe the improved mechanism for actuating the compression abutment valve.

15 Referring to Fig. 1, 57 designates a cam which is provided with a hub 58, the latter being suitably fixed to the rotor shaft 7. Spokes 58' radiate from said hub. Shaft 44, of compression valve 42, has a bearing in hub 59, and shaft 45 has a bearing in hub 60. On the outer end of shaft 44, a gear wheel 61 is mounted. On the outer end of shaft 45, gear wheel 62 is mounted. A gear wheel 63, having a hub 64 mounted on shaft 7, synchronizes the movement of compression valve 43 with compression valve 42. I will now take up the specific mechanism for actuating compression valve 42.

A cam actuated arm, which is conveniently 30 in the form of an elbow arm, is designated at 65 and is pivotally mounted at 66 to a fixed part of the engine casing. At the elbow of said arm, the same is provided with a roller 67 which projects into the closed 35 cam 57 for engagement with the various configurations of the channel cam path formed in cam 57, and generally designated at 68. At the remaining end of said arm 69, there is pivoted a valve actuating pitman bar 70, 40 the upper end of which is pivoted at 71 to gear wheel 61, off center with respect thereto. Projecting from the lower end of said pitman bar 70 is a lug 72 on the opposite sides of which are secured springs 73 and 45 74. The springs 73 and 74 co-act with lugs, which I am about to describe, for the purpose of moving the valve 42, and of course the valve 43, over a dead center position as regards the connection of bar 70, at 71, with 50 the gear wheel 61. On the up stroke, or over the upper dead center, the spring 73 is engaged by a series of lugs 75, on the cam wheel, and placed under tension to throw the upper end of bar 7 to the right, over 55 a dead center position. Spring 74, is engaged by lugs 76, on spokes 58, for throwing the bar 70 over a dead center position, below, or radially inwardly of the axis of shaft 44.

60 Referring to Fig. 4 it will be seen that the cam 57, or rather the cam path 68 thereof, has concentric valve holding sections 77. There would necessarily be four of these sections by reason of the fact that the rotor 65 has four pistons. A quick actuating in-

cline 78 actuates valve 42 to cause the latter to ride up piston face 54, under accelerated speed, in order to close the valve 42 into its compression chamber and permit the piston to pass. The cam path has a holding section 79, which is concentric, and which holds the valve 42 in the position shown in Fig. 3, while the piston 13 is passing across curved face 53, and until the piston 13 reaches the hub convex portion 49. It will be noted 70 that one of the lugs 75 is now approaching spring 73. As the roller 67 reaches the incline 80, then the compression valve is shifted from the position shown in Fig. 3, to dispose its curved face 52 in wiping engagement with the edge of piston 13, and the pivotal connection of the bar 70 with wheel 61 has reached a point approximately that of upper dead center. Fig. 5 shows the roller 67 traveling upwardly on the actuating 80 incline 80. At this point the lug 75 has engaged and tensioned spring 73 so that the latter will be imparting a thrust on bar 70 to positively turn the pivot 71 over upper dead center. This position is indicated 85 in Fig. 6, wherein the roller 67 has reached an apex section 81, in the cam path 68, where the spring has been tensioned so as to throw the bar 70 over an upper dead center. As the roller 67 passes over this apex section 81, 90 and at which point the piston 13 has just reached engagement with section 56 of wall 6, then the roller 67 enters a sharp declivity section 82 which lowers the cam actuated arm, causing the pivotal connection 71 to 100 move clockwise about and downwardly to the right of shaft 44. This sharp and sudden movement is effective to cause the edge 46, of valve 42 to ride quickly down the rear face 57, of piston 13, and into peripheral 105 engagement with the rotor, whereupon the roller 67 will enter the concentric holding portion 77 and the valve 42 will be held in this position, as shown in Fig. 2, until the roller 67 reaches the next declivity 110 section 78, of the cam path, whereupon the operation will be repeated. Thus all that has been shown in Fig. 4 will be quadrupled to make the entire cam path complete. When the arm moves down to a lowermost point, 115 and in order to get pivotal connection 71 beyond lower dead center, below shaft 44, then one of the lugs 76 will engage and tension spring 74 and positively throw the bar 70 to the left of shaft 44 and out of a dead 120 center position.

It will thus be seen that the jointed arm construction comprising arm 65 and bar 70, together with springs 73 and 74, and lugs 75 and 76, constitute broadly, cam actuated, 125 rotary valve actuated mechanism with means for throwing the mechanism over dead center position, either radially outwardly or inwardly of the shaft.

As has been previously stated, the intake 130

valves, 36 and 37, are oscillatory valves and I will now describe the means whereby the same are actuated.

A cam 83 having hub 84 is fixed on engine 5 shaft 7. Valve 37 is mounted upon shaft 85 and valve 36 is mounted on shaft 86. On the outside of each shaft is an arm similar to that shown at 87, and the arms are connected by a cross-bar 88 whereby actuation 10 of shaft 86 will similarly actuate shaft 85. Arm 87 is provided with a sector of teeth 89, adapted to mesh with a sector of teeth 90, formed on one end of an oscillating arm 91. Arm 91 is pivoted to the casing of the 15 engine, at 92, and has a roller 93, which projects into the cam path 94 of cam 83.

Referring to Fig. 9, it will be seen that the roller 93 is traversing a concentric holding section 95, of the cam path 94, and that 20 in this position, the intake valves 36 and 37 will be in the position shown in Fig. 3, with their arcuate abutment faces presented against the edges of the pistons. As the pistons rotate in a clock-wise direction so that 25 they pass the intake valve, which is substantially the position shown in Fig. 9, then the roller 93 will enter a sharp declivity 96 which will oscillate the valves 36 and 37 in contra-clockwise and clockwise directions. 30 respectively, from the positions shown in Fig. 3 to the positions shown in Fig. 2. The intake valves will be held in this position by the roller 93 traversing an inner holding section 97, of the cam path, until the next 35 following piston approaches to the position shown in Fig. 2. Then the roller 93 will reach a sharp inclined section 98, as shown in Fig. 8, and this will oscillate the valves 36 and 37 in clock-wise and contra-clock- 40 wise directions with a view of bringing the arcuate abutment faces abreast of the pistons, as shown in Fig. 3. Fig. 7 shows the roller 93 just entering the inclined section 98. It will now be clear that these sharp 45 inclined sections 96 and 98 provide for the accelerated movement of the intake valves out from in front of approaching pistons, to ride upon the same, and pass into the intake chambers, and also to cause the valves 50 to quickly reenter into peripheral engagement with the rotor after the pistons have passed the valves. It will be understood that, referring to Fig. 2, when piston 16 has passed the intake valve, it will have closed 55 rearward egress of the charge being compressed, and the piston 15 will then be commencing to egress the burnt gases.

I will next describe my improved packing, with special reference to Figs. 10, 11 60 and 12, as regards intake valve 37.

Opposite portions of the valve are longitudinally grooved, as indicated in Fig. 12, at 99. Intermediate packing strips 100 are seated in said groove and are held therein 65 for slight longitudinal movement by means

of counter-sunk headed pins 101, extending through slots 102, in the strip. Each end of this intermediate packing strip has a tongued terminal 103 which slidely fits into a forked terminal 104 of an angle strip 70 105. The end of the angle strip 105, as indicated at 106, in Fig. 2, extends radially inwardly across the end face of the valve and is provided with a forked terminal 107. A shaft packing section 108 extends from 75 the shaft toward the terminal 107 and is provided with a tongue 109 that slidely fits said forked terminal 107. An expansively acting spring 110 may be interposed at the tongue and the bight of the fork to 80 normally expand the tongue and forked portion. However, main reliance is upon the pressure itself entering the slightly separated ends in its endeavor to escape, and exerting pressure, supplemental to the 85 springs, to force the packing strips from each other and thereby tighten engagement of the packing strips against the walls of the portions with which they co-act to prevent leakage. The angle pieces may be held 90 from too great movement by the pins 111 fitting loosely through an aperture to provide slight play.

The pistons are provided with identically the same type of packing, as indicated generally at 112, and which need not be described in detail. Likewise, the compression valves are provided with identically the same type of packing, as indicated generally at 113, and which need not be described in detail. The packing 112 extends transversely along the edge of each piston, and the packing 113 extends transversely along the edge of each compression valve, and therefore it will be seen that the pistons 105 always have gas-tight engagement with the rotor periphery 6, and with the compression valves, and the intake valves, whereas the intake and compression valves likewise have gas-tight packing contact with the 110 rotor. Pins 114 hold the angle packing strip against too great outward movement.

I realize that a specific form of packing is a separate and distinct invention from an engine, and therefore the packing has been 115 described sufficiently for the same to be understood, and has only been briefly claimed in this application for the purpose of providing a foundation for divisional application later to be filed.

I claim:—

1. In a rotary engine, a casing having intersecting rotor and compression chambers, a rotor in said rotor chamber having a piston movable in one direction toward said 125 compression chamber to compress a charge therein and away from said chamber to be actuated by such compressed charge, a valve in said compression chamber, and means moving said valve toward the advancing 130

piston to form an abutment for and force the compressed charge into said compression chamber and let the piston pass, said means holding said valve in a position of rest to engage one face thereof with the edge of the piston during its travel passed said valve and then rotate said valve into engagement with said piston as it recedes from said chamber to open said chamber and release the compressed charge for action against said piston.

2. In a rotary engine, a rotor having a piston, a casing forming compression and rotor chambers, a valve in said compression chamber for coaction with said rotor and its piston, and means holding said valve in a position of rest while engaging said rotor when the advancing piston is compressing a charge into said compression chamber, said means moving said valve along said advancing piston into said compression chamber at an accelerated speed with respect to the speed of said piston to trap the compressed charge in said compression chamber and permit said piston to pass said valve.

3. In a rotary engine, a rotor having a piston, a casing forming compression and rotor chambers, a valve in said compression chamber having a rotor engaging portion for coaction with the periphery of said rotor and said piston, and means holding said valve in a position of rest with said portion engaging the periphery of the moving rotor while the advancing piston is compressing a charge into said compression chamber, said means moving said valve into said compression chamber with said portion engaging said piston to trap the compressed charge in said compression chamber and permit the piston to pass said valve.

4. In a rotary engine, a casing having rotor and compression chambers, a rotor in said rotor chamber having a piston for compressing a charge into said compression chamber, a valve for said compression chamber having a substantially flat rotor abutment engaging face portion, and means driven by said rotor for imparting variable movement to said valve to maintain said portion in face abutting engagement with said rotor as the advancing piston compresses a charge into said compression chamber and holding said portion in abutting face engagement with and up and along said advancing piston to trap the compressed charge in said compression chamber.

5. In a rotary engine, a casing having rotor and compression chambers, a rotor in said rotor chamber having a piston provided with a concavely curved face for compressing a charge into said compression chamber, a valve for said compression chamber having an edge portion, and means holding said valve in a position of rest with said edge

portion in engagement with the rotating rotor while said piston is compressing a charge into said compression chamber and actuating said valve with said edge portion traveling along said curved face of said piston and into said compression chamber to trap the compressed charge therein.

6. In a rotary engine, a casing having compression and rotor chambers, a rotor in said rotor chamber having a convexly curved portion and provided with a piston having a concavely curved face merging into said convexly curved rotor portion and adapted to compress a charge into said compression chamber, a rotary valve for said compression chamber having a rotor and piston engaging portion, and means holding said valve in a position of rest with said rotor and piston engaging portion engaging said convex rotor portion while said piston is compressing a charge into said compression chamber and suddenly moving said valve at an accelerated rate when the curved portion of said piston reaches said valve to advance said rotor and piston engaging portion along said piston face and into said compression chamber to permit said piston to pass said valve and trap the compressed charge in said compression chamber.

7. In a rotary engine, a casing having a rotor and a compression chamber, a rotor in said rotor chamber having a piston, a valve in said compression chamber having a piston engageable face, and actuating means for holding said valve driven by said rotor for holding said valve in a position of rest for wiping engagement of said piston along said face as said piston passes said compression chamber.

8. In a rotary engine, a casing having rotor and compression chambers, a rotor in said rotor chamber having a piston, a rotary valve in said compression chamber having curved piston engageable faces, and actuating means holding said valve in a position of rest while said piston is in wiping engagement along one of said curved surfaces and then slightly shifting said valve and holding the same in a position of rest while said piston is in wiping engagement with another curved surface of said valve.

9. In a rotary engine, a casing having rotor and compression chambers, a rotor in said rotor chamber having a piston provided with a concavely curved explosion face, a valve for holding a compressed charge in said compression chamber, and actuating means operated by said rotor for suddenly moving said valve at an accelerated rate of speed with respect to the speed of travel of said piston to engage said valve along said curved piston surface and release the compressed charge from said compression chamber behind the receding piston.

10. In a rotary engine, a casing having rotor and compression chambers, a rotor in said rotor chamber having a piston provided with a concavely curved compression face, a 5 valve for trapping a charge compressed by said piston into said compression chamber, and actuating means operated by said rotor for imparting accelerated movement to said valve to engage the latter along the curved 10 face of said piston and move said valve into said compression chamber to trap the compressed charge therein and permit the piston to pass said valve.

11. In a rotary engine, a casing having intersecting rotor and intake chambers, a 15 rotor in said rotor chamber having a piston, an oscillatory abutment valve in said intake chamber, mechanism operated by said rotor for rotating said valve into peripheral contact with said moving rotor and holding said valve in a position of rest to form an abutment for the in-coming charge and open intake to said rotor chamber, and said mechanism rotating said valve at an accelerated 20 speed in engaging contact with the advancing piston to preserve abutment engagement and close intake to said rotor chamber.

12. In a rotary engine, a casing having intersecting rotor and intake chambers, a 30 rotor in said rotor chamber having pistons, the pistons having concavely curved compression faces merging into the periphery of said rotor, a semi-cylindrical abutment valve in said intake chamber, and mechanism driven by said rotor to engage the cylindrical face thereof with the periphery of said rotor to form a gas abutment and open intake to said rotor abutment, and said mechanism oscillating said valve in another 35 direction against the compression face of the advancing piston to preserve the abutment and close intake to said rotor chamber.

13. In a rotary engine, a casing having intersecting rotor and intake chambers, a 45 rotor in said rotor chamber having a piston provided with a concavely curved compression face merging into the periphery of said rotor, a semi-cylindrical abutment valve in said intake chamber, and mechanism driven 50 from said rotor for oscillating said valve to engage its cylindrical face with the periphery of the moving rotor to form a gas abutment and open intake of gas to said rotor chamber, and said mechanism rotating said 55 valve in one direction against the curved face of said advancing piston to preserve the gas abutment and close intake to said rotor chamber, said valve having an arcuate face for engagement with the edge of the 60 piston as the latter is passing said valve to further preserve the gas abutment.

14. In a rotary engine, a casing having intersecting rotor and intake chambers, a 65 rotor in said rotor chamber having a piston, a rotary abutment valve in said intake cham-

ber, mechanism driven by said rotor for rotating said valve into peripheral contact with the moving rotor to form an abutment against escape of the in-coming charge and open intake to said rotor chamber, and said mechanism rotating said valve in another direction into sliding engaging contact with the advancing piston to preserve the abutment and close intake to said rotor chamber, said valve having an abutment face for engagement with the edge of said piston while the latter is passing said valve.

15. In a rotary engine, a casing having intersecting rotor and intake chambers, a 80 rotor in said rotor chamber having pistons, said rotor chamber having an exhaust outlet in advance of said intake chamber with respect to the direction of rotation of said rotor, an abutment valve in said chamber, and mechanism driven by said rotor for rotating said valve into peripheral contact with the moving rotor to open intake to said rotor chamber and form an abutment behind the charge inducing piston and in front of the gas exhausting piston, and said mechanism rotating said valve in another direction to close intake and let the exhausting piston pass after the burnt gases have been 90 discharged through said outlet, said valve having an abutment face for engagement with the edge of said exhausting piston to prevent escape of the induced charge backwardly passed said valve.

16. In a rotary engine, a casing having intersecting rotor and intake chambers, a 100 rotor in said rotor casing having pistons, said rotor chamber having an exhaust outlet in advance of said intake chamber with respect to the direction of rotation of said rotor, an abutment valve in said chamber, 105 and mechanism driven by said rotor for moving said valve into engagement with the periphery of the moving rotor to open intake to said rotor chamber and form an abutment behind the charge inducing piston and in front of the gas exhausting piston, and said mechanism rotating said valve in another direction to close intake and let the exhausting piston pass after the burnt gases have been 110 discharged through said outlet.

17. In a rotary engine, a casing having a rotor chamber and intake and compression chambers intersecting said rotor chamber, a rotor in said rotor chamber, having pistons, a rotary compression valve, co-acting with 120 the compression chamber and the rotor to form an abutment in front of an approaching piston for a charge being compressed and behind the receding piston to back up an exploded charge, and an intake valve co-acting with said compression chamber and the rotor to form an abutment in front of a burnt charge being exhausted and behind an incoming induced charge, and cam mechanism for imparting rotary movement to 125 130

said compression valves and oscillatory movement to said intake valve, substantially as described.

18. In a rotary engine, a casing having a rotor chamber and a compression chamber intersecting the rotor chamber, a rotor in said rotor chamber having pistons, a rotary compression valve co-acting with said chamber

ber and the rotor and pistons, cam mechanism for intermittently actuating said rotary valve, and means for throwing said rotary valve over dead center, substantially as described.

In testimony that I claim the foregoing as my own, I hereby affix my signature.

ALBERT C. ASHCRAFT.
